(57) **CLAIM**

The ornamental design for a storage drive, as shown and described.

DESCRIPTION

FIG. 1 is a top, front and side perspective view of a first embodiment of a storage drive in a first position embodying the new design.

FIG. 2 is a top view thereof.

FIG. 3 is a bottom view thereof.

FIG. 4 is a back view thereof.

FIG. 5 is a front view thereof.

FIG. 6 is a first side view thereof.

FIG. 7 is a second side view thereof.

FIG. 8 is a top, front and side perspective view of the first embodiment in a second position.

FIG. 9 is a top view thereof.

FIG. 10 is a bottom view thereof.

FIG. 11 is a back view thereof.

FIG. 12 is a front view thereof.

FIG. 13 is a first side view thereof.

FIG. 14 is a second side view thereof.

FIG. 15 is a top, front and side perspective view of a second embodiment in a first position shown broken away for indeterminate length.

FIG. 16 is a top view thereof.

FIG. 17 is a bottom view thereof.

FIG. 18 is a back view thereof.

FIG. 19 is a front view thereof.

FIG. 20 is a first side view thereof.

FIG. 21 is a second side view thereof.

FIG. 22 is a top, front and side perspective view of a second embodiment in a second position embodying the new design shown broken away for indeterminate length.

FIG. 23 is a top view thereof.

FIG. 24 is a bottom view thereof.

FIG. 25 is a back view thereof.

FIG. 26 is a front view thereof.

FIG. 27 is a first side view thereof; and,

FIG. 28 is a second side view thereof.

Broken lines are used to illustrate features of the storage drive which form no part of the claimed design.
